LADY'S HANDBAG OR THE LIKE

Sidney Hyman, New York, N. Y.

Application January 29, 1952, Serial No. 268,730

4 Claims. (Cl. 150—28)

1

This invention relates to new and useful improvements in ladies' handbags or the like.

More specifically, the present invention proposes the formation of a lady's handbag having an outer perimetral shell engaged fixedly in position about an inner body member in a manner so that the shell will have at least one open side to be closed by a closure flap hingedly secured to the outer shell.

Still further, the present invention proposes forming the outer perimetral shell of an elongated strip of material folded in position about the inner body member to bring its end edges into adjacency with the closure flap attached thereto in such a manner that the flap functions to hold the end edges in contact with one another.

As a further object of the present invention, it is proposed to position the inner body member within the outer perimetral shell so that it functions as a bottom wall for the handbag so that the open side which is to be closed by the closure flap will be at the top of the handbag.

Another object of the present invention proposes providing means for releasably retaining the closure flap in its position closing the open top of the handbag and to further provide the top face of the closure flap with a handle by which the handbag can be conveniently carried in the closed position of the closure flap.

The present invention proposes a modification of the handbag in which the inner body member is positioned centrally within the outer perimetral shell forming a partition dividing the interior of the outer shell into separate compartments accessible through opposed open sides of the outer perimetral shell.

A further object of the present invention proposes forming the closure flap to have an intermediate portion secured to the outer perimetral shell over its bottom meeting end edges and two opposed pivotal flap portions for independently closing the opposed open sides of the outer perimetral shell.

As a still further object of the present invention, it is proposed to provide separate means for holding each of the flap portions of the closure flap in its position closing the respective open side of the outer shell.

It is a further object of the present invention to construct ladies' handbags of the type disclosed which are simple and durable, which are effective for their intended purposes and which can be manufactured and offered for sale at a reasonable cost.

2

For further comprehension of the invention, and of the objects and advantages thereof, reference will be had to the following description and accompanying drawings, and to the appended claims in which the various novel features of the invention are more particularly set forth.

On the accompanying drawings forming a material part of the present disclosure:

Fig. 1 is a perspective view of a lady's handbag constructed in accordance with the present invention.

Fig. 2 is a view similar to Fig. 1, but showing the closure flap in its open position.

Fig. 3 is a rear elevational view of Fig. 1.

Fig. 4 is an enlarged transverse sectional view taken on the line 4—4 of Fig. 1.

Fig. 5 is an enlarged partial sectional view taken on the line 5—5 of Fig. 2.

Fig. 6 is an enlarged partial horizontal sectional view taken on the line 6—6 of Fig. 3.

Fig. 7 is a developed view of the blank used for forming the outer perimetral shell.

Fig. 8 is a developed view of the blank used for forming the inner body member.

Fig. 9 is a developed perspective view of the closure flap.

Fig. 10 is a perspective view of a lady's handbag constructed in accordance with a modification of the present invention.

Fig. 11 is a view similar to Fig. 10, but showing one of the flap portions of the closure flap in its open position.

Fig. 12 is a bottom plan view of Fig. 10.

Fig. 13 is an enlarged transverse sectional view taken substantially on the line 13—13 of Fig. 10.

Fig. 14 is an enlarged partial vertical sectional view taken on the line 14—14 of Fig. 12.

Fig. 15 is an enlarged detailed sectional view of one of the closure flaps taken on the line 15—15 of Fig. 11.

The lady's handbag, according to the first form of the present invention illustrated in Figs. 1 to 9, includes a perimetral outer shell 20. The outer shell 20 is formed of an elongated strip of material 21 that has its top and bottom longitudinal edges bound by strips of resinous plastic material 22. The strips of resinous plastic material 22 are secured in position by lines of stitches 23.

Fitted within the outer perimetral shell 20, there is an inner body member 24. The inner body member 24 is shaped from the blank shown in Fig. 8, which has a central wall 25 bounded at its four sides by the laterally extended walls 26.

Thus, the blank from which the inner body

3 member 24 is shaped is substantially of cruciform outline. The walls 26 of the inner body member are arranged to be folded upward along the lines 27 shown in Fig. 8 so that the end edges of the walls 26 are brought into contact with one another forming substantially an open topped box.

The blank from which the outer perimetral wall 20 is formed is of a length corresponding to the periphery of the central wall 25 of the inner body member 24. The outer perimetral wall 20 is designed to be folded vertically along the lines 28, shown in Fig. 7, to be engaged about the outer faces of the upstanding walls 26 of the inner body member 24 to provide a front wall 29, end walls 30 and adjacent rear wall portions 31. The end edges of the blank used for forming the outer perimetral wall 20, which define the inner edges of the rear wall portions 31 are brought into adjacency when the outer perimetral wall is wrapped about the inner body member 24.

The inner body member 24 is positioned within the outer perimetral shell 20 with the bottom face of its central wall 25 flush with the bottom edges of the perimetral outer shell so that the central wall 25 functions as a bottom wall for the handbag. The walls 26 are of a height to have their top edges located immediately below the bottom edge of the inner portion of the upper strip of binding material 22, see Fig. 4. That arrangement of the inner body member 24 within the outer shell 20 leaves at least one side—the top side—of the handbag open.

A closure flap 32 is provided for closing the open top side of the handbag. The closure flap 32 is formed of a piece of rigid but bendable material 33, bounded on its four sides by a strip of resinous plastic material 34 secured in position by lines of stitches 35.

The closure flap 32 is folded in half horizontally along the line 36 shown in Fig. 9, to provide a top flap portion 37 and depending portion 38. With the flap portion 37 positioned to close the open top side of the handbag, the depending portion 38 is depended along the outer faces of the rear flap portion 31 of the outer perimetral shell 20. The depending portion 38 is secured in position by means of rivets 39 which are passed through the depending portion, the rear wall portions 31 and the adjacent wall 26 of the inner body member 24. The rivets 39 are located at the four corners of the depending portion 38 on opposite sides of the adjacent end edges of the blank from which the outer perimetral wall is formed. The locations of the rivets 39 function to hold the end edges in adjacency and further maintain the outer perimetral wall 20 in position about the walls 26 of the inner body member 24. With the rivets 39 passing through the adjacent wall 26 of the inner body member, the inner body member 24 is retained against dropping out of the bottom of the outer perimetral wall 20.

Means is provided for retaining the flap portion 31 in its position closing the open top of the handbag. The flap portion retaining means comprises an elongated tab 40 which is extended vertically along the outer face of the front wall 29 of the outer perimetral shell 20. One end of the tab 40 is secured to the front wall 29 by spaced rivets 41, which pass through the front wall 29 and the adjacent wall 26 of the inner body member 24. Thus, the rivets 41 function in conjunction with the rivets 39 to support the inner body member 24 against dropping out of the bottom of the outer perimetral shell 20.

4 The free end of the tab 40 is provided for extension partially across the top face of the flap portion 31 at its free front edge.

5 That free end of the tab 40 is provided with a snap fastener element 42 for engagement with a complementary snap fastener element 43 mounted through the flap portion 31. When the snap fasteners 42 and 43 are engaged, as shown in Fig. 1, the flap portion 31 will be retained in its closed position.

10 Mounted at spaced positions on the top face of the flap portion 31 of the closure flap 32, there are inverted U-shaped members 44 between which a handle 45 is extended so that the handbag can be conveniently carried when the top flap portion 31 is retained in its closed position by the engaged fastener elements.

15 Extended along the inner face of the top flap portion 31, there is an elongated piece of resinous plastic material 45 which has its end edges inserted beneath the strip of binding material 34 of the closure flap and secured in position by the lines of stitches 35. Thus, the piece of resinous plastic material 45 provides a pocket on the inner face of the flap portion 31 for a mirror 46. The piece of resinous plastic material 45 is formed intermediate of its ends with spaced slits 47 for mounting a comb 48.

20 The strip of material 21 of the outer shell 20, the main portion of the blank used for forming the inner body member 24 and the piece of material 33 of the closure flap 32 are all formed of the same material. Those parts can be formed of suitable rigid but bendable resinous plastic materials. On the other hand, those parts can be made of a rigid cardboard material which has its outer face covered by a sheet of resinous plastic material adhesively secured thereto.

25 The present disclosure is not intended to be limited in any way to the specific use of any particular material for forming the three main parts of the handbag.

30 Referring specifically to Fig. 6, it will be noted that the vertical end edges of the walls 26 of the inner body member 24 which are free of any connection to the outer shell 20 are located outside of the end edges of the walls 26 which are held in position by the rivets 39 and 41. By that arrangement those free walls 26 of the inner body member are retained in position against the inner faces of the end walls 30 of the outer perimetral shell 20.

35 In the modification of the invention illustrated in Figs. 10 to 15, the outer perimetral shell 20' is wrapped vertically about the inner body member 24' to have a top wall 29', end walls 30' and bottom wall portions 31'. The bottom wall portions 31' have adjacent end edges contacting one another beneath the inner body member 24'.

40 The inner body member 24' is positioned within the outer perimetral shell 20' with its central wall 25' located centrally of the width of the outer shell 20' to form a partition dividing the interior of the outer shell into separate compartments 50 and 51 located on opposite sides of the central wall 25' of the inner body member 24'. Entrance to the compartments 50 and 51 is by way of the adjacent open sides of the outer shell 20'.

45 The closure flap 32' has an intermediate portion 38' extended across and secured to the bottom face of the bottom wall portions 31' by means of rivets 39'. Certain of the rivets 39', as best shown in Fig. 13, pass through the adjacent walls 26 of the inner body member 24' to retain

the inner body member fixedly in position within the outer shell 20'.

Integrally extended from the intermediate portions 38' there are vertically extended flap portions 37' for closing the two open sides of the outer perimetral shell 20'. Peripheral edges of the flap portions 37' are bound by metallic binding strips 34' that are crimped into position on the flap portions, see Fig. 15.

Elongated tabs 40' are fixedly attached to the top wall 29' of the outer perimetral shell 20' by means of rivets 41'. One of the rivets 41', see Fig. 13, is also inserted through a wall 26 of the inner body member 24' to further assist the pair of rivets 39' in securing the inner body member in position within the outer perimetral shell 20'. There is a tab 40' for each of the flap portions 37' and each tab has its free end depended along the outer face of the respective flap portion. Mounted on the free ends of the tabs 40' there are snap fastener elements 42' engageable with complementary snap fastener elements 43' disposed on the outer faces of the flap portions 37'. Thus, when the snap fasteners 42' and 43' are engaged each of the compartments 50 and 51 will have its open side closed by its respective flap portion 37'.

Mounted on the top face of the top wall 29' of the outer perimetral shell 20' there is a single inverted U-shaped member 44'. The U-shaped member 44' is located substantially mid-way between the attached ends of the tabs 40' and has extended upward therefrom a carrying handle 49'.

In all other respects, the modification of the invention described in connection with Figs. 10 to 15 is similar to the first form and like reference numerals are used to identify like parts.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A lady's handbag comprising a perimetral outer shell, an inner body member fixedly positioned within said outer shell, said outer shell having at least an open upper side, a closure flap hingedly secured to said outer shell for closing the said open side, and means releasably retaining said closure flap in its position closing the open side of said shell, said outer shell being formed of an elongated strip of material having its longitudinal edges bound and being folded at right angles to said longitudinal edges to be extended completely about said inner body member, said inner body member having a central wall bounded by right angularly extended walls extended along the inner faces of said outer shell, said outer shell being wrapped horizontally about said inner body to have a front wall, end walls and rear wall portions having adjacent vertical end edges, and a carrier handle mounted on top of said flap.

2. A lady's handbag comprising a perimetral outer shell, an inner body member fixedly positioned within said outer shell, said outer shell having at least an open upper side, a closure flap hingedly secured to said outer shell for closing the said open side, and means releasably retaining said closure flap in its position closing the

open side of said shell, said outer shell being formed of an elongated strip of material having its longitudinal edges bound and being folded at right angles to said longitudinal edges to be extended completely about said inner body member, said inner body member having a central wall bounded by right angularly extended walls extended along the inner faces of said outer shell, said outer shell being wrapped horizontally about said inner body to have a front wall, end walls and rear wall portions having adjacent vertical end edges, said inner body member being positioned within said outer shell with its central wall flush with the bottom of said outer shell to form a bottom wall leaving the top side of said outer shell open, and a carrier handle mounted on top of said closure flap.

3. A lady's handbag comprising a perimetral outer shell, an inner body member fixedly positioned within said outer shell, said outer shell having at least an open upper side, a closure flap hingedly secured to said outer shell for closing the said open side, and means releasably retaining said closure flap in its position closing the open side of said shell, said outer shell being formed of an elongated strip of material having its longitudinal edges bound and being folded at right angles to said longitudinal edges to be extended completely about said inner body member, said inner body member having a central wall bounded by right angularly extended walls extended along the inner faces of said outer shell, said outer shell being wrapped horizontally about said inner body to have a front wall, end walls and rear wall portions having adjacent vertical end edges, said inner body member being positioned within said outer shell with its central wall flush with the bottom of said outer shell to form a bottom wall leaving the top side of said outer shell open, and a carrier handle mounted on top of said closure flap.

4. A lady's handbag comprising a perimetral outer shell, an inner body member fixedly positioned within said outer shell, said outer shell having at least an open upper side, a closure flap hingedly secured to said outer shell for closing the said open side, and means releasably retaining said closure flap in its position closing the open side of said shell, said outer shell being formed of an elongated strip of material having its longitudinal edges bound and being folded at right angles to said longitudinal edges to be extended completely about said inner body member, said inner body member having a central wall bounded by right angularly extended walls extended along the inner faces of said outer shell, said outer shell being wrapped horizontally about said inner body to have a front wall, end walls and rear wall portions having adjacent vertical end edges, said inner body member being positioned within said outer shell with its central wall flush with the bottom of said outer shell to form a bottom wall leaving the top side of said outer shell open, and a closure flap having a top flap portion extended across the open top side of said outer shell and an integral depending portion depended along the outer faces of said rear wall portions, and means securing together said depending portion, said rear wall portions and the adjacent wall of said inner body member, and a carrier handle mounted on top of said closure flap.

5. A lady's handbag comprising a perimetral outer shell, an inner body member fixedly positioned within said outer shell, said outer shell having at least an open upper side, a closure flap hingedly secured to said outer shell for closing the said open side, and means releasably retaining said closure flap in its position closing the open side of said shell, said outer shell being formed of an elongated strip of material having its longitudinal edges bound and being folded at right angles to said longitudinal edges to be extended completely about said inner body member, said inner body member having a central wall bounded by right angularly extended walls extended along the inner faces of said outer shell, said outer shell being wrapped horizontally about said inner body to have a front wall, end walls and rear wall portions having adjacent vertical end edges, said inner body member being positioned within said outer shell with its central wall flush with the bottom of said outer shell to form a bottom wall leaving the top side of said outer shell open, and a closure flap having a top flap portion extended across the open top side of said outer shell and an integral depending portion depended along the outer faces of said rear wall portions, and means securing together said

7
depending portion, said rear wall portions and
the adjacent wall of said inner body member, said
retaining means comprising a tab secured at one
end to the front wall of said outer shell, and
means releasably attaching the other end of said
tab to the top face of said flap portion of said
closure flap adjacent its free front edge, and a
carrier handle mounted on top of said closure
flap.
